COAT HANGER ADAPTER

Joseph E. Lynch, Burbank, Calif., assignor, by direct and mesne assignments, to Lynford Products Company, Los Angeles, Calif., a corporation of California

Application July 11, 1949, Serial No. 3,828

Term of patent 14 years

(Cl. D80—8)

To all whom it may concern:

Be it known that I, Joseph E. Lynch, a citizen of the United States, and a resident of the city of Burbank, in the county of Los Angeles and State of California, have invented a new, original, and ornamental Design for a Coat Hanger Adapter, of which the following is a specification, reference being had to the accompanying drawings, forming part thereof, in which:

Fig. 1 is a front view of a coat hanger adapter showing my new design;

Fig. 2 is a top view thereof;

Fig. 3 is an end view thereof;

Fig. 4 is a cross-sectional view, taken along the line 4—4 of Fig. 1; and

Fig. 5 is a cross-sectional view, taken along the line 5—5 of Fig. 1.

The opposite side is similar to that shown in Fig. 1.

I claim:

The ornamental design for a coat hanger adapter, as shown and described.

JOSEPH E. LYNCH.
